BEAD CHAIN

Valentine J. Taubner, 741 S. Fulton Ave.,
Mount Vernon, N.Y.

Filed Feb. 17, 1964, Ser. No. 78,644

Term of patent 14 years

(Cl. D45—16)

FIG. 1

FIG. 2

FIG. 1 is a side elevational view of a bead chain showing my new design, a portion thereof being depicted by broken lines to indicate indeterminate length; and FIG. 2 is a perspective view thereof of several of the component beads together, upon an enlarged scale.

I claim:

The ornamental design for a bead chain, substantially as shown and described.
